UNITED STATES PATENT OFFICE.

OMER F. CAMPBELL, OF FRESNO, CALIFORNIA.

LIFE-SAVING AND SPORTING DEVICE.

Application filed September 3, 1920. Serial No. 407,933.

To all whom it may concern:

Be it known that I, OMER F. CAMPBELL, a citizen of the United States, residing at Fresno, in the county of Fresno and State 5 of California, have invented new and useful Improvements in Life-Saving and Sporting Devices, of which the following is a specification.

It is the object of the present invention 10 to provide a suit adapted to be worn by a person and which will form buoyant means for supporting the person in the water.

It is a further object of the invention to 15 provide a construction including means for conveniently supplying air to the person while wearing the suit.

It is a still further object of the invention to provide a device including means for supplying various conveniences in order that 20 the person wearing the suit may live in the water for an appreciable length of time in the event of shipwreck or the like.

The invention will be readily understood from the following description of the accompanying drawings, in which—

Figure 1 is a front elevation of the suit.

Fig. 2 is a side elevation of the same.

Fig. 3 is a rear elevation of the suit.

Fig. 4 is an enlarged front elevation of 30 the helmet of the suit.

Fig. 5 is a transverse section on the line 5—5 of Fig. 4.

Fig. 6 is an enlarged front elevation of the pump mechanism for the suit.

Fig. 7 is a detail front elevation of one of 35 the connecting members for the device.

Fig. 8 is a longitudinal section on the line 8—8 of Fig. 7.

Fig. 9 is a similar view to Fig. 5 showing 40 the helmet open.

The device consists essentially of a suit of flexible material drawn over the legs, body and arms of a person, and a helmet, preferably, of metal connected to the suit so as to be received over the head.

The suit is shown as comprising legs 1, body portion 2 and arms 3. The helmet consists of a rear portion 4 and a front plate 5, said rear portion and front plate of the helmet terminating in shoulder ribs 6 and 7, hinged together as shown at 8 to swing in a substantially vertical plane. The shoulder and neck portion of the suit is received between the ribs 6 and 7 of the helmet and 55 within the neck portion 9 thereof in such manner as to form a water tight joint be-

tween the suit and the helmet. The ribs 6 and 7 are shown as extending in a substantially vertical plane down over the shoulders a sufficient distance to form a rigid support 60 for the person wearing the device. The helmet will thus support the head of the person in upright position even should he become unconscious.

Shoes 10 are worn upon the feet over the 65 legs 1 of the suit which, preferably, envelop the feet, said shoes, preferably, being weighted so as to retain a person wearing the suit in upright position within the water. The shoes may be connected to the 70 legs 1 by any suitable detachable connection 11. The arms 3, preferably, terminate in gloves 12' and paddles 12 may be worn upon the hands to assist in swimming.

The rear member 4 and front plate 5 of 75 the helmet are, preferably, provided at their meeting edges with annular ribs 13 and 14 forming a continuation of the shoulder ribs 6 and 7. When the helmet is in closed position upon a person's head connecting means 80 are provided for securing said ribs together for forming a water tight connection. The interior of the helmet is, preferably, padded as shown at 30.

The face portion 15 of front plate 5 is, 85 preferably, hinged thereto as shown at 16 so that the face plate may be swung downwardly when it is not required to retain the helmet in a water tight condition. The face plate is also provided with an annular rib 17 90 in which is arranged connecting means for providing a water tight closure for the face plate. The face plate may be provided with eye openings 18 arranged to receive transparent plates 19. A mouth opening closed 95 by a plate 20 having fastening means is also provided in the face plate, said closure plate being, preferably, hinged at its lower edge 21 so that it may swing downwardly into open position. When, however, the person 100 wearing the device is submerged the plate 20 will swing upwardly so as to form a closure for the mouth opening, and said plate may also be manually closed.

An illuminating device shown as an 105 electric lamp 22 may be mounted upon the top of the helmet, said lamp being connected by the conductor cord 23 to a battery 24 carried upon the suit. A handle 25 is also, preferably, provided upon the top of 110 the helmet to assist in lowering or raising the person wearing the suit to or from the water.

When the device is not in use the suit portion thereof may be folded and packed within the helmet and the handle 25 will form ready means for transporting the same.

- 5 A knapsack 26 may be carried upon the back, said knapsack being shown as connected to the suit by an eyelet 27 therein engaging a hook 28 upon the lower edge of the helmet. This knapsack may be provided 10 with a closure plate 29 arranged to provide a water proof closure. The knapsack may be employed for carrying food or the like.

The connecting means employed for fastening closure plates 20 and 29 in position 15 and for fastening the rib 17 of face plate 15 in position and also for fastening ribs 6 and 7 and 13 and 14 together, preferably, consists of pins 31 adapted to be received through the parts to be held together and 20 provided with heads 32 abutting against said parts. The other ends of the pins are provided with transverse members 33 adapted to be received through slots 34 in one of the connected members and then turned so that 25 said transverse members will extend across the slots. Cam surfaces 35 are, preferably, provided upon the slotted members so as to be engaged by transverse members 33 for drawing the connected parts tightly together when the pins 31 are turned. By this 30 construction water proof joints may be provided.

A toilet receptacle 37 may be carried upon the suit, said receptacle being adapted to be 35 used by unfastening the helmet and slipping one arm from arm 3 of the suit.

A receptacle adapted to contain air is received around the waist of the suit in order 40 to form buoyant means for supporting the person wearing the device in water. This receptacle is shown as a tube 40 retained in position by means of straps 41. The means employed for filling the tube with air may consist of a pump cylinder 42 fixed upon the 45 suit. A piston 43 is arranged to be reciprocated within the pump cylinder by means of the pump handle 44, said piston being equipped with an upwardly opening check valve so that when said piston is moved 50 downward any fluid within the lower portion of the cylinder 42 will automatically open the check valve in said piston and pass into the chamber within the cylinder above said piston. The lower end of the pump 55 cylinder communicates by way of pipe 45 which is provided with a check valve 46 with a two-way valve 47. This valve is arranged to be manually turned so as to make communication with either conduit 48 or conduit 60 49. These conduits are arranged as pipes extending down within the respective legs 1 to a point adjacent the toes.

The lower end of pump cylinder 42 also 65 communicates by way of conduit 50 with a cross valve 51 arranged to be manually ac-

tuated so as to open conduit 50 to a nipple 52 leading to the atmosphere, or arranged to shut off conduit 50 from nipple 52 and open a discharge nozzle 53 to a conduit 54 communicating with the upper end of the pump 70 cylinder. The upper end of the pump cylinder is also provided with a conduit 55 having a check valve 56 therein and communicating with the tube 40.

In operation with valve 47 closed and 75 valve 51 turned so that conduit 50 is open to the atmosphere, when the pump is actuated air will be drawn in through nipple 52 to the pump cylinder and will be forced outwardly therefrom through conduit 55 to 80 the tube 40. When it is desired to employ the pump for pumping out any water which may have accidentally leaked into the suit, valve 51 is turned to cause communication between nozzle 53 and the pump cylinder, and valve 85 47 is turned so as to cause communication between either conduit 48 or 49 and the pump cylinder. When, now, the pump is actuated a pumping action will be provided in the leg 90 of the suit having its conduit in communication with the pump cylinder, any water pumped by said pumping action being discharged through conduit 54 and nozzle 53.

A conduit 60 leads from tube 40 to the interior of the suit, said conduit being closed 95 by a valve 61. By this arrangement air may be supplied to the interior of the suit to increase the buoyancy thereof and also to provide air to be breathed by a person wearing the suit when the helmet is closed. This air within the suit may be discharged past an outwardly opening check valve 62 provided in the helmet of the device.

An oxygen tank 63 is, preferably, provided upon the suit, said tank having a conduit 64 leading to the tube 40. This conduit may be controlled by a valve 65. The oxygen tank is also connected with the interior 100 of the suit as by a conduit 66 controlled by a valve 67. By this arrangement through suitable manipulation of the controlling 110 valves oxygen may be supplied to the interior of the suit or oxygen may be supplied to the tube 40.

Various changes may be made without departing from the spirit of the invention as claimed.

What is claimed is:

1. The combination with a buoyant suit, of a helmet comprising members hinged together to swing in a substantially vertical plane, and cam means for securing said members in contact.

2. The combination with a buoyant suit, of a helmet comprising hinged members, a face plate separately hinged to one of said members, and means for detachably securing said members and said plate in contact.

3. The combination with a buoyant suit, of a helmet secured to said suit and having 130

- side ribs extending down over the shoulders to form supporting means for the helmet relative to said suit.
4. In a life saving device, a helmet formed in two parts, diverging members extending outwardly and downwardly from the lower portions of said parts, and the lower ends of the diverging members being hinged to each other.
- 10 5. In a life saving device, a helmet formed in two parts, diverging members extending outwardly and downwardly from the lower portion of said parts, the lower ends of the diverging members being hinged to each other, and a face plate hinged to the front portion of the front member of said helmet.
- 15 6. In a life saving device, a helmet formed in two parts, diverging members extending outwardly and downwardly from the lower portion of said parts, the lower ends of the diverging members being hinged to each other, a face plate hinged to the front portion of the front member of said helmet, and cam devices for securing said members in contact.
- 20 7. In a life saving device, a helmet comprising a pair of members adapted to receive the head of the wearer, diverging arms extending outwardly and downwardly from
- the lower portions of said members, the lower portions of which arms are hinged to each other, a face plate hinged to the front member of the helmet, and means for detachably connecting marginal portions of the members of the helmet and said diverging arms.
- 25 8. In a life saving device, a helmet comprising a pair of members adapted to receive the head of the wearer, diverging arms extending outwardly and downwardly from the lower portions of said members, the lower portions of which arms are hinged to each other, a face plate hinged to the front member of the helmet, and cam means for detachably connecting marginal portions of the members of the helmet and said diverging arms.
- 30 9. In a life saving device, a helmet formed in two parts, the lower portions of which are hinged to each other, a face plate hinged to the front part of the helmet, a pad arranged on the interior of the other part of the helmet, and an outwardly opening check valve carried by said helmet and provided with a stem extending into said pad.
- 35 40 45 50 55
- In testimony whereof I have signed my name to this specification.

OMER F. CAMPBELL.
